J. T. BEASLEY

AUTOMATIC FIRE ALARM

Filed Oct. 15, 1923

Inventor

John T. Beasley,
By *M. Edwards*,
Attorney

UNITED STATES PATENT OFFICE.

JOHN T. BEASLEY, OF BLAKELY, GEORGIA.

AUTOMATIC FIRE ALARM.

Application filed October 15, 1923. Serial No. 668,737.

To all whom it may concern:

Be it known that I, JOHN T. BEASLEY, a citizen of the United States, residing at Blakely, in the county of Early and State 5 of Georgia, have invented certain new and useful Improvements in Automatic Fire Alarms; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to automatic fire alarms wherein the action of the heat causes a parting or break in a system of lines or wires thus automatically actuating an alarm sounding apparatus which also indicates the 20 location of the fire.

The principal object of my invention is to provide an apparatus of the character to be described which not only can be concealed from view and thus avoid the unsightly appearance resulting from the usual method 25 of installation of such devices but as a result of its peculiar method of support will possess their advantages of efficiency and also be able to detect more promptly those 30 fires which have their origin in elevator or dumb-waiter shafts and thus work their way in between the walls of the building.

With these objects in view and such others as may appear as the description proceeds, 35 reference will be had to the accompanying drawing in which

Figure 1 represents a vertical section of a building having my invention installed, the annunciating member being represented 40 on a considerably larger scale than the rest of the figure in order that the connections of my device thereto may be the more readily shown, and

Figure 2 is an enlarged detail showing the 45 manner in which my device is supported.

My invention as shown consists essentially of two members or groups of parts A and B which are duplicates one of the other, each member consisting of an upper and lower 50 part a' , a'' and b' , b'' , respectively, each of which off-sets or balances the other. For the upper part a' of the member A, I bore in the wall or partition of the room two pairs of holes 1 and 2, the holes of each pair 55 being in a vertical line. Similarly for the lower part a'' of member A, I bore two pairs

of holes 3 and 4, the holes of each pair being in a vertical line, also the holes of pair 3 being in line with those of pair 1 and those of pair 4 being in line with those of pair 60 2, the holes of pairs 1 and 2 and those of pairs 3 and 4 marking approximately the corners of a rectangle. The pairs of holes 5 and 6 of part b' and 7 and 8 of part b'' are similarly placed. Snugly fitting these 65 holes are the pairs of discs 9, 10, 11, 12, 13, 14, 15, 16, the discs of the respective pairs being connected by lengths of fusible wire, these lengths being somewhat longer than the distance between the discs and forming 70 loops or bends 17, 18, 19, 20, 21, 22, 23, 24, said loops or bends passing over pulleys 25, 26, 27, 28, 29, 30, 31, 32 respectively, the pulleys 25 and 26 being pivotally mounted at the ends of a short bar 33, pulleys 27 and 28 pivotally mounted at the ends of a short bar 34, and pulleys 29 and 30 and pulleys 31 and 32 being similarly mounted at the ends of short bars 35 and 36 respectively. At the centers of bars 33, 34, 35 and 36 I pivotally mount pulleys 37, 38, 39 and 40 respectively, pulleys 37 and 38 being on adjacent sides of bars 33 and 34 respectively and pulleys 39 and 40 being on adjacent sides of bars 35 and 36 respectively, so that a cord 80 or cable passed over pulleys 37 and 38 and placed under tension will tend to draw bars 33 and 34 together and create a tension in wires 17, 18, 19 and 20 and similarly a cable passed over pulleys 39 and 40 and placed 90 under tension will tend to draw bars 35 and 36 together and produce a tension in wires 21, 22, 23, and 24. Between bars 33 and 34 and on opposite sides of a line joining their middle points I mount pulleys 41 and 42 and between bars 35 and 36 and on opposite sides of a line joining their middle points I mount pulleys 43 and 44. These pulleys are mounted on the inside of the lathing or directly 95 on the wall in the case of a wood partition. In the wall framing joist at the side of member A opposite from member B I place a screw eye 45, and on the side of member B away from member A to the joist, I attach a pulley 46 by bracket 47. I have shown 100 diagrammatically a form of annunciator which can be operated by my apparatus. A casing 48 contains the usual electric bell circuit 49 which operates the bell 50 and which contains the switch lever 51 normally held 105 in open position by spring 61, which makes and breaks the circuit at 52 in the manner 110

to be described. To screw eye 45 I attach a flexible wire or cord 53 and pass same successively over pulleys 41, 37, 38 and 42 of member A, thence to pulleys 43, 39, 40 and 44 of member B, thence to pulley 46. The direction of the cord from this point is dependent upon the location of the annunciator. As shown in the drawing the annunciator is on the floor below the room in which the apparatus has been described and hence cord 53 will pass downward to the floor below, thence over pulley 54 to the room in which the annunciator is located, thence over pulley 55, thence downward to annunciator 48. At the point where cord 53 passes lever 51 said cord 53 carries a flat plate 56 having a longitudinal slot 57 through which lever 51 passes. In the lower part of casing 48, cord 53 carries a plate 58 bearing the number of the room whence cord 53 comes, and at the lower extremity cord 53 carries a weight 59. The door of casing 48 has an opening 60 through which plate 58 can be seen when alarm is sounded. Under normal conditions the cord 53 being attached to screw eye 45 and weight 59 at its extremity will be held under tension and in a condition of equilibrium, but when a fire occurs in the immediate neighborhood of the apparatus and one of the fusible metal discs 9, 10, etc., or one of the fusible wire loops 17, 18, etc. is melted by the heat this destroys the equilibrium in the system and slackens the tension on the cord 53 and immediately weight 59 drops. This brings down the lever 51 against spring 61 closing the circuit at 52, thus sounding the alarm. At the same time plate 58 bearing the location of the room drops into view opposite the opening 60. While I have described the holes 1, 2, etc. laid out generally in rectangular form, that is not necessary, the essential point being that the discs 9, 10, etc. shall form triangles with their respective pulleys 25, 26, etc., the purpose of which is obvious from the drawing. And while I have shown my invention installed in the walls of a house it can be used equally well in the ceiling or under the flooring. And further while I have shown the device in its preferred form with individual cords leading from the several rooms, a common cord might be taken from the annunciator and branch off in individual cords to the several rooms. And further, while for clearness I have shown but one switch lever 51 it is obvious that a separate lever may be used for each cord or slotted plate, or an individual lever may be passed through the sev-

eral plates 57. And further, while the discs 9, 10, etc. are shown as being visible in rooms C and D, a coating of paint or wall paper will render the whole apparatus invisible. In a private dwelling, the annunciator can be placed in the cellar or in the hallway.

Instead of an electric alarm, any ordinary mechanically operated gong mechanism released upon movement of the lever 51 to give an alarm may be used, and which is not illustrated in detail because not involving invention.

Having described my invention and set forth its merits, what I claim is:

1. In a device of the character described, a plurality of discs of fusible material fitted in cavities formed in a support, fusible wires connecting said discs in pairs, a cord taking a staggered course relatively to said fusible wires, suspension bars provided with pulleys lying in loops of the fusible wires and connecting one set of said wires with another set, means for holding said cord under tension, means carried by said cord for setting off an alarm when tension is removed, and means carried by said cord for indicating location of ruptured members, as and for the purpose described.

2. In a device of the character described, a plurality of discs of fusible material, fusible wires connecting said discs in pairs, swinging suspension bars provided with pulleys lying in loops of the fusible wires, a cord taking a staggered course relatively to the suspension bars and connected therewith, means for holding said cord under tension and means carried by said cord for setting off an alarm mechanism when tension is removed, as and for the purpose described.

3. In a device of the character described, a plurality of discs of fusible material, fusible wires connecting said discs in pairs, pulleys carrying said fusible wires, bars for pivotally mounting said pulleys in pairs, a third pulley mounted on each of said bars in opposed relation to each of said pairs of pulleys, a cord taking a staggered course relatively to said last mentioned pulleys, means for holding said cord under tension, and means carried by said cord for setting off an alarm mechanism when tension is removed as and for the purpose described.

In testimony whereof I affix my signature in presence of two witnesses.

JOHN T. BEASLEY.
